(57) **CLAIM**

The ornamental design for a television apparatus, as shown and described.

DESCRIPTION

2. Television Apparatus

2.1: Front

2.2: Back

2.3: Left

2.4: Right

2.5: Top

2.6: Bottom

2.7: Perspective

2.8: Perspective

2.9: Partial Enlarged

2.1-2.9 are drawings showing an embodiment of the television apparatus. Reproduction 2.9 shows a partial enlarged view of a part of the television apparatus. The present product is used for playing audio and video. The broken lines in the drawings are for the purpose of illustrating portions of the television apparatus that form no part of the claimed design.

1 Claim, 8 Drawing Sheets
